UNITED STATES PATENT OFFICE.

SIMEON F. PIERCE, OF ST. PAUL, MINNESOTA.

GAS-BURNER.

1,242,234.

Specification of Letters Patent.

Patented Oct. 9, 1917.

Application filed December 11, 1915. Serial No. 66,317.

To all whom it may concern:

Be it known that I, SIMEON F. PIERCE, a citizen of the United States, residing at St. Paul, in the county of Ramsey and State of 5 Minnesota, have invented certain new and useful Improvements in Gas-Burners, of which the following is a specification.

My invention relates to improvements in incandescent gas burners, its object being 10 particularly to provide means for more thoroughly mixing the air and gas than in the ordinary burner, and in coöperation therewith improved pilot light means, the features of construction of the burner being 15 such as to coöperate in stabilizing the flow of gas to the mantle and at the same time protect the pilot light.

To this end the invention consists in the features of construction, combination, and 20 arrangement of parts hereinafter described and claimed.

In the accompanying drawings forming part of this specification,

Figure 1 is an elevation and section of the 25 burner and supported mantle;

Fig. 2 shows an adaptation of my features of invention to a depending mantle and burner;

Figs. 3 and 4 are enlarged sections taken 30 on line $x-x$ of Fig. 2 showing the gas controlling valve in closed and open positions respectively;

Fig. 5 is an elevation of a post supported street lamp embodying my features of invention and provided with an auxiliary lighter 35 for the mantle; and

Fig. 6 is a sectional elevation taken at right angles to Fig. 5.

Referring to the drawings, A represents 40 a gas inlet tube threaded into the gas discharge or nozzle member 2. The member 2 is formed with a transverse opening 3 into which is fitted the rotatable valve 4, said valve carrying an arm 5 on its outer end, to 45 which is detachably connected an actuating rod 6, said rod being slidable in a bracket 7 on the post 8, and being adapted to be held in adjusted positions by a suitable screw 9. The 50 valve is formed with a transverse middle opening 11 adapted, when the valve is turned into the position shown in Fig. 4, to bring the inlet opening 12 into communication with the outlet openings 13 and 14. In the 55 upper ends of the outlet openings 13 are

threaded the gas discharge nipples 15. In the central opening 14 is threaded a tube 16 which extends upwardly and terminates underneath the bottom gauze of the gas mantle to form a pilot light, as shown in Fig. 1. 60

Having threaded support upon the nozzle member 2 is a cap 17 having a constricted open end forming a central outlet opening 18 and also forming a threaded support for the base 19 of the mantle supporting cylinder 20. The cylinder 20 at its lower end supports an inner cylinder 21, which inner cylinder has an outwardly flared lower end 22 joined to the bottom of the outer cylinder. The base 19 of the mantle supporting cylinder 70 is formed with vertical openings 23 and side openings 24 connected with the interior of the inner tube 21. The tube 20 supports in the usual manner the cap 25 which cap is formed with a top gauze 26 constituting 75 the mantle bottom and supports a bracket 27 from which is hung in the ordinary manner the mantle 28.

The inner tube 21 supports a second tube 29, which second tube supports in its upper 80 end a head 30 through which head extends the pilot light tube 16. The head 30 is formed with a cup shaped top 31, which forms a protecting chamber for the pilot light, as well as a controlling deflector for 85 the main flow of gas. The tube 29 is formed with side gas openings 32 below the deflector head 30. Supported in the lower end of the tube 29 is an inside tube 33, said inside tube 33 being spaced from the tube 29 with 90 its lower end flared outwardly and connected with said tube. The upper end of the tube 33 terminates short of the openings 32. The tube 29 is also formed with openings 34 adjacent to its lower end. 95

In Fig. 2 is shown the above described features adapted for use with a depending mantle. In the adaptation shown in Fig. 2 the deflector head forms the bottom of the chamber 36, from which chamber tubes 37 100 lead inside the main gas tubes 38 to the mantles. The main gas tubes 38 lead from the cylinder 20 and at their ends form a support for the mantles not shown.

In order that the pilot light may remain 105 burning when the valve is turned as shown in Fig. 3 to cut off the gas, I form a groove 40 surrounding the valve so as to connect the supply tube with the pilot light tube when the valve is turned into closing position. 110

To use as an auxiliary pilot light to light the mantle in case the pilot light happens to be out, I provide a tube 41 supported in a bracket 42 alongside the gas inlet, said tube 41 being connected by a conduit 43 with the groove 40 around the valve. The tube 41 extends below the bottom of the lamp casing 44, as shown in Fig. 5, and is rotatable within in the bracket so as to be turned into or out 10 of communication with the gas containing groove 40. The tube 41 is provided with side openings 45 both below the lamp and alongside the mantle. With the tube turned into the gas receiving position shown in 15 Fig. 6 the gas may be lighted at the lower openings 45 and will travel up the perforated side of the tube until it reaches the perforations alongside the mantle whereby to light the mantle and relight the pilot light.

20 In use with the valve 4 closed, as shown in Fig. 3, the main supply of gas will be shut off, the gas will travel around the groove 40 into the outlet opening 14 and pass through the tube 16 to the pilot light. With 25 the valve 4 open, as shown in Fig. 4, the gas will also pass through the nipples 15 up through the tubes 21 and 33 and out through the lateral openings of the tube 29 upwardly past the head 30 into the mantle. The head 30 will turn the gas outwardly against the sides of the mantle to prevent sucking out 30 the pilot light. The cup formed in the top of the head 30 forms a receptacle for the pilot light protecting it against being put 35 out by the snapping back of the gas, wire gauze 26 also aiding in this respect. Air is drawn in through the openings 23 and 24 to mix with the gas in the ordinary manner. The inlet tube 33 is shown projecting above 40 the openings 34 of the tube 29. Thus the gas rises against the cupped bottom 46 of the head 30, is deflected downwardly and passes out of the openings 32. Some of the gas which is deflected by said cupped portion 45 46 is forced downwardly along the edge of the tube 29 on account of the pressure of the gas and escapes through the openings 34 (instead of passing downwardly into the tube 21). The cupped top 46 forms a stop 50 and stabilizer for the gas.

I claim:

1. In a gas burner, a valve casing having a valve seat, a main passage and a laterally directed passage leading from the seat, a 55 valve engaged on the seat and provided with a peripheral groove establishing constant communication with the lateral passage, a bracket threaded in the lateral passage of the casing and provided with a valve 60 seat having communication with the said lateral passage, a rotatable valve engaged on the latter valve seat and being formed with an axial duct opening through both ends, and a tube threaded on each end of the

last valve and provided with a longitudinal series of perforations. 65

2. In a gas burner, a valve casing having a nozzle discharge that is externally threaded, a cap for the nozzle engaged with the threads thereof and provided with a contracted outlet that is externally screw threaded, a base threaded on the contracted mouth of the cap and formed with vertical air passages, a pilot tube carried by the valve casing and extending upwardly 70 through the cap mouth and base, a pair of gas discharge nipples threaded on the casing and arranged in converging relation and terminating in the cap mouth, and a mixing tube mounted on the base. 75

3. In a gas burner, a valve casing, a valve therein, a cap threaded on the casing and provided with a contracted mouth, a base member threaded on the contracted mouth of the cap and provided with vertical air 85 passages, an outer cylinder mounted on the base member, an inner cylinder having a flared base portion threaded in the lower part of the outer cylinder and extending upwardly therein, and a mixing device 90 threaded on the upper end of the inner cylinder and disposed within the outer cylinder. 95

4. In a gas burner, a valve casing, a valve therein, a cap threaded on the casing and provided with a contracted mouth, a base secured on the mouth of the cap and provided with vertical air passages, an outer cylinder mounted on the base, an inner cylinder arranged within the outer cylinder 100 and provided with a flared base portion threaded engaged with the lower part of the same, a tube threaded in the upper end of the inner cylinder and provided with side openings, a head closing the upper end of the tube, and an inside tube having a flared base portion threaded in the lower part of the first tube and terminating short of the upper end of the latter. 105

5. In a gas burner, a valve casing, a pilot tube extending therefrom, a cap engaged with the casing and provided with a mouth contracted partially about the tube, a base mounted on the cap mouth and provided with vertical air passages, an outer cylinder 110 on the base, an inner cylinder carried by the outer cylinder with its upper portion spaced inwardly therefrom, a tube threaded on the upper end of the inner cylinder and provided with upper and lower series of openings, an inside tube having a flared base secured to the lower end of the second tube and extending to a point between the series of openings, and a head closing the upper end of the second tube and receiving the 115 pilot tube. 120

6. In a gas burner, a lamp casing, a burner therein, an igniting tube extending from

70

80

110

120

130

without through the casing and alongside the burner, said tube being provided with a series of closely arranged perforations extending lengthwise of the tube, a valve for the burner, and a conduit leading from the valve and rotatably supporting the tube whereby the latter may be rotated to serve as a valve for the perforation of said tube.

In testimony whereof I affix my signature in presence of two witnesses.

SIMEON F. PIERCE.
